US00D527261S

(12) United States Design Patent (10) Patent No.: US D527,261 S
(45) Date of Patent: * Aug. 29, 2006

(54) LID

(75) Inventor: Manfred Hörnke, Rotterdam (NL)

(73) Assignee: Unilever Bestfoods, North America, division of Conopco, Inc., Englewood Cliffs, NJ (US)

() Term: 14 Years

(21) Appl. No.: 29/199,816

(22) Filed: Feb. 19, 2004

(30) Foreign Application Priority Data

Aug. 22, 2003 (GB) 3014165

(51) LOC (8) Cl. 09-07

(52) U.S. Cl. D9/454

(58) Field of Classification Search D9/454, D9/449, 447, 445, 439, 438, 435, 452; D7/638, D7/511, 510, 392, 392.1; D3/323; 220/270-271, 220/709, 718, 781; 215/254

See application file for complete search history.
